UNITED STATES PATENT OFFICE.

WILLIAM M. MITCHELL, OF LOUISVILLE, KENTUCKY.

RAIL-ANCHOR.

1,244,356.

Specification of Letters Patent. Patented Oct. 23, 1917.

Application filed August 24, 1917. Serial No. 187,915.

To all whom it may concern:

Be it known that I, WILLIAM M. MITCHELL, a citizen of the United States, and a resident of Louisville, county of Jefferson, 5 and State of Kentucky, have invented certain new and useful Improvements in Rail-Anchors, of which the following is a specification.

The improvement relates to anchors for preventing the longitudinal creeping of railway rails and seeks to provide a cheap, simple form by which the spikes which secure the rail to the cross ties can be utilized to prevent creeping. It has heretofore been 10 proposed to prevent creeping of the rail by providing its base with a notch for receiving one of the spikes or by providing a bar bolted to the rail and arranged to engage a spike, but such constructions necessarily cut 15 away and weaken the metal body of the rail. It has also been proposed to weld the spikes to the rail. While such a construction avoids weakening the metal body of the rail, it is open to the objection that the 20 wave motion of the rail effected by the passage of heavy trains will cause the spike to work up and down in the tie and injure it. It has also been proposed to weld tie plates to the rail so that they will coöperate with 25 30 spikes extending therethrough into the ties to prevent creeping, but with this construction the rails and tie plates cannot be readily renewed separately.

In accordance with the present invention 35 a short metal lug is fused or welded at its inner end to one side of the rail base, projects outwardly over the rail seating face of the tie or tie plate and engages or coöperates with one of the spikes to prevent the longitudinal 40 creeping of the rail. Such a construction is extremely cheap and efficient, can be readily applied and does not affect or interfere with the ordinary operation or renewals of the rails, spikes, ties and tie plates, 45 except that it effectively prevents the creeping of the rail. The essential features of the invention are hereinafter more fully set forth, are illustrated in the accompanying drawing and more particularly pointed out 50 in the appended claims.

In the drawings Figure 1 is a plan view of a railroad rail equipped with the present invention. Fig. 2 is a section on the line

2—2 of Fig. 1. Fig. 3 is a plan view showing other forms of the invention. Fig. 4 55 is a section on the line 4—4 of Fig. 3.

The rail 10 rests on the upper seating faces of the ties 11 or, as indicated in Figs. 3 and 4, upon the rail seating tie plates 12 interposed between the base of the rail and 60 the ties. The rail is preferably secured to the ties as usual, by spikes 13 driven into the ties with the spike heads overlapping the edge portions of the rail base.

The anchors for preventing the creeping 65 of the rail are in the form of short metal lugs separate from the spikes and tie-plates and preferably formed of short sections of flat bars of forged iron or steel.

The flat metal lug 14 shown applied to the 70 right-hand side of the rail in Figs. 1 and 2, abuts against and is fused or welded to the edge of the rail base, projects outwardly therefrom over and in contact with the upper rail-seating face of the tie and is cut 75 away or notched to provide a recess 15 through which the rail-retaining spike 13 passes, the opposite edges of the recess forming abutments that engage the opposite sides of the spike to prevent creeping of the rail. 80

The anchor lug 14 can be readily welded to the edge of the rail base by using a portable oxy-acetylene torch to fuse together the adjacent portions of the rail base and lug. But preferably the upper portion of the 85 inner edge of the lug is cut away or beveled and, while the adjacent edge portions of the rail base and anchor are heated nearly to the fusion point, metal fused from a steel rod is run into the space between them to form 90 a fillet, as indicated at *a*. The fillet is thus united or incorporated with the metal of the rail base and anchor lug so that the latter is permanently secured to the rail base without weakening the metal body 95 thereof.

The anchor lug 16 shown applied to the left hand side of the rail in Figs. 1 and 2, is made from a short section of a flat, forged iron or steel bar and is offset between its 100 ends to form a shoulder 17 that abuts against the inner edge of the rail base and an inner end portion 18 that overlaps the upper face of the rail base. The parts are fused or welded to the upper face and edge portion 105 of the rail preferably by added metal fillets

extending about the edge of the inner portion of the anchor lug as indicated at *b*. In this form, the rail-retaining spike 13' extends through an opening 19 in the outer 5 projecting portion of the lug.

- The anchor lug 20 shown at the left-hand side of Figs. 3 and 4 is similar to the anchor lug 16 except that it does not directly engage a rail retaining spike, but instead abuts 10 against the edge of the tie plate 12 which is held against movement by the spikes. The anchor lug shown applied to the right-hand side of the rail in Figs. 3 and 4 is formed of two members 21, which project outwardly 15 from the edge of the rail base over the face of the tie plate and form a spike receiving recess 22 between them which registers or is in line with one of the spike holes in the plate. The lug members 21, in the form 20 shown, are, like the lugs 16 and 20, provided with shoulders 17 and inner end portions 18 engaged and secured to the edge and upper face of the adjacent base flanged by welding fillets *b*.
25. The improved rail anchoring means is inexpensive, can be readily applied, does not interfere with the ordinary operation and renewals of the spikes and tie-plates, and effectively cooperates with the spikes to prevent creeping without requiring the use of more spikes than are usually employed in securing the rail in position. Changes may be made in the details set forth without departure from the essentials of the invention 30 as defined in the claims.

I claim as my invention:—

1. The combination with a rail, a supporting cross-tie having a rail seat, and a spike for securing the rail to the tie, of 40 a short metal anchor-lug extending outwardly from the rail base over the face of said rail seat and engaging said spike, the inner end portion of said lug being fused or welded at its edge to one side of the rail.
45. 2. The combination with a rail, a supporting cross-tie having a rail seat, and a spike for securing the rail to the tie, of a short metal lug having the inner end portion thereof engaging and fillet-welded at 50 its edge to the base flange of the rail, said lug extending outwardly over the face of said rail seat and engaging said spike to thereby hold the rail against creeping.
55. 3. The combination with a rail, its supporting cross-tie and a spike driven into the tie with the head engaging one of the base flanges of the rail, of an anchor comprising a short metal lug engaging said spike and fused or welded to the base flange at a 60 point adjacent said spike.
65. 4. The combination with a rail and a supporting cross-tie having a rail seat, of a spike driven into the tie adjacent the rail, a short metal anchor-lug projecting outwardly from the rail base over the face of said rail

seat and engaging said spike, said lug being fused or welded at its inner end to the rail base at a point adjacent said spike.

5. The combination with a rail, a supporting cross-tie having a rail seat, and a spike for securing the rail to the tie, of a short metal anchor fused or welded to the rail base at a point adjacent said spike and projecting outwardly from the rail base over the face of said rail seat, said anchor having a recess the edges of which engage the opposite sides of said spike to hold the rail against creeping.

6. The combination with a rail, its supporting cross tie, a rail seating plate on said tie, and a spike extending through said plate and into said tie and engaging the rail base, of a separate anchor comprising a metal lug fused or welded at its inner end to one side of the rail and coöperating with said spike 85 to hold the rail against creeping.

7. The combination with a rail, its supporting cross-tie, a rail seating plate on said tie, and a spike extending through said plate and into said tie, of an anchor comprising 90 a metal lug fused or welded at its inner end to one side of the rail and extending outwardly over the face of said plate and engaging said spike.

8. The combination with a rail, its supporting cross-tie, a rail seating plate on said tie, and spikes extending through said plate and into said tie, of an anchor fused or welded at the inner end to one side of the rail and extending outwardly over the face 100 of said plate and having a spike engaging recess in line with one of the spike holes in said plate.

9. The combination with a rail, a supporting cross-tie, and a spike driven into said tie adjacent the rail base, of an anchor comprising a short, flat metal lug projecting outwardly from the rail base and engaging said spike, said lug having a part abutting against the edge of the rail base and the inner end portion of said lug being fillet-welded at its edge to the rail base.

10. The combination with a rail, a supporting cross-tie, and a spike driven into said tie adjacent the rail base, of an anchor comprising a short, flat metal lug projecting outwardly from the rail base and engaging said spike, said lug having a shoulder abutting against the edge of the rail base and an inner end portion overlapping and welded to the upper face of the rail base.

11. A one-piece rail anchor formed of a short section of a flat metal bar adapted to abut against and be fused or welded to one of the flanges of the rail base and to project 125 outwardly therefrom over the rail seating face into engagement with a rail-retaining spike.

12. A one-piece rail anchor formed of a short section of a flat metal bar offset be- 130

tween its ends to form a shoulder arranged to abut against the edge of the rail base, an inner portion arranged to overlie and be fused or welded to the upper face of the rail 5 base and an outer portion arranged to extend outwardly over the rail seat and engage a rail-retaining spike.

13. The combination with a rail, a supporting cross tie, a rail seating plate on said 10 tie and a spike extending through said plate and into said tie, of a separate anchor comprising a metal lug fused or welded to an exposed face of one of the base flanges of the

rail and coöperating with said spike to hold the rail against creeping. 15

14. The combination with a rail, a supporting cross tie, a rail seating plate on said tie, of a rail retaining spike extending through said plate and into said tie, of a separate anchor comprising a metal lug fused 20 or welded to an exposed face of one of the flanges of the rail base and projecting outwardly therefrom, said lug engaging said plate and coöperating with said spike to hold the rail against creeping.

WILLIAM M. MITCHELL.
